UNITED STATES PATENT OFFICE.

WILLIAM R. HASTINGS, OF LEAVENWORTH, KANSAS.

MAIL-BOX SUPPORT.

Application filed November 13, 1923. Serial No. 674,526.

To all whom it may concern:

Be it known that I, WILLIAM R. HASTINGS, citizen of the United States, residing at Leavenworth, in the county of Leavenworth and State of Kansas, have invented 5 certain new and useful Improvements in Mail-Box Supports, of which the following is a specification.

This invention relates to certain new and 10 useful improvements in mail box supports, particularly adapted for use in connection with the mail or letter boxes on rural free delivery routes.

The primary object of the invention is 15 to provide a simple and durable form of mail box support of the character mentioned above, which may be cheaply and easily manufactured and placed into use, and which will effectively serve its intended 20 purpose for a long period of time, while presenting a neat and desirable appearance.

Another object of the invention is to provide a mail box support of the above kind, by means of which the mail box will be 25 positioned most conveniently for permitting the mail carrier to insert letters to be delivered into the same, while at the same time mounting the mail box in a yieldable manner so that the same will not become 30 seriously damaged should it be struck by a moving object.

Other objects will become apparent as 35 the nature of the invention is better understood, and the same consists in the novel form, combination, and arrangement of parts hereinafter more fully described, shown in the accompanying drawing and claimed.

In the drawing, wherein like reference 40 characters indicate corresponding parts in the two views:

Figure 1 is a side elevational view of 45 a mail box support constructed in accordance with the present invention, and shown with a mail box operatively secured thereon, the mail box being partly broken away to reveal a detail of the invention, and

Figure 2 is a top plan view of the support shown in Figure 1.

Referring more in detail to the drawing, 50 the present support embodies an upright or post adapted to have its lower end suitably rigidly anchored in the ground in any of the numerous well known ways of anchoring posts, and comprising a lower relatively long section 5 that is preferably formed of

a length of pipe, an intermediate relatively shorter section 6 that is formed of a section of similar pipe to that employed for the section 5, and that is coupled to the latter section by means of a T-fitting 7, the lateral branch of which, as indicated at 8, is of smaller size than the cross head or head portion thereof. The post further embodies an upper still shorter section or nipples 9, that is coupled to the intermediate section 6, by means of a T-fitting 10 similar to the fitting 7, and that has its upper end suitably closed by means of a screw cap 11 or the like, said fitting 10 having a smaller 65 lateral branch 12 similar to the branch 8 of the fitting 7 as shown clearly in Figure 1.

A pair of superimposed T-fittings 13 and 14 are respectively rigidly connected with 70 the T-fittings 7 and 10, by means of relatively short nipples 15 and 16, the opposite ends of which are threaded respectively into the branches of the fittings 7 and 13, and 10 and 14. The cross head portions of 75 the fittings 13 and 14 thus provide vertical aligned bearings in which is rotatably mounted the vertical arm 17 of a horizontally swinging bracket that also includes a horizontal outwardly projecting upper arm 80 rigid with the depending vertical arm 17. The vertical arm 17 of the bracket is preferably formed of a length of pipe section, closed at its lower end by means of a screw 85 cap 18 and coupled to one end of the upper horizontal arm of the bracket through the medium of an elbow 19 that rests upon the upper edge of the cross head portion of the upper fitting 14. This, in effect, provides a vertical thrust bearing for the 90 swinging bracket, while the cap 18 prevents upward displacement of the arm 17 from the lower bearing 13.

The upper horizontal arm of the swinging bracket, preferably consists of an outer 100 pipe section 20, and an inner pipe section 21, that are coupled together by means of a four way fitting 22, the inner section 21 being connected to the elbow 19 and a T-fitting 23 being threaded upon the outer 105 end of the outer section 20 as shown clearly in Figure 2. Threaded into the opposite ends of the lateral branches of the fittings 22 and 23 are relatively short oppositely extending 110 pairs of pipe sections 24 and 25 respectively, which have screw caps 26 and 27 threaded upon the outer ends thereof, and form trans-

verse or horizontal spaced parallel cross bars on the upper horizontal arm of the swinging bracket. This mail box, generally indicated at A and which is of conventional 5 form is rigidly secured upon the upper arm of the swinging bracket and the cross bars thereof preferably through the medium of U-bolts 28 that embrace the arm sections 20 and 21 inwardly of each of the fittings 22 and 23 and which have their shanks extended through pairs of openings in the bottom of the mail box A for reception of nuts which are threaded tightly against the upper 10 surface of the bottom wall of said box.

15 A helical spring 29 surrounds the arm 17 of the swinging bracket between the bearings 13 and 14, and one end of this spring is attached to one of said last named bearing, while the other end of said spring is attached to the arm 17, in such manner as to normally yieldingly hold the upper horizontal arm of the swinging bracket in an outwardly extending position as shown in Figure 1, whereby the mail box is supported 20 in a most convenient manner for permitting the mail carrier to readily place letters therein. Also, it will be seen that the springs 29 will permit the bracket to swing, should a moving object strike the mail box 25 or the bracket, whereby damage to the device or the mail box is effectively prevented 30 under ordinary conditions.

From the above description, it is believed that the construction and operation, as well

as the advantages of the present invention 35 will be readily understood and appreciated by those skilled in the art.

What I claim as new is:

In a mail box support of the character described, a post comprising a relatively 40 long lower pipe section, a relatively shorter intermediate pipe section, a still shorter upper pipe section, and a pair of spaced T-fittings connecting said sections in a vertically aligned end to end relation, a second 45 pair of T-fittings, a nipple rigidly connecting each of said last named T-fittings with one of the first named pair of T-fittings, a bracket including horizontal and vertical 50 arms, the vertical arms of the bracket being journaled in the second named pair of T-fittings, means to rigidly secure a mail box upon said horizontal arm, yieldable means associated with said vertical arm and one of said second named pair of T-fittings for 55 normally yieldingly holding the horizontal arms in outwardly swung position relative to the post, said horizontal arm comprising a pair of sections joined in end to end relation by a four way fitting, a T-fitting upon 60 the outer section of said horizontal arm, and horizontal laterally extending pipe sections secured in the lateral branches of the last named four way and T-fittings to form cross bars upon which the mail box rests. 65

In testimony whereof I affix my signature.

WILLIAM R. HASTINGS.
